UNITED STATES PATENT OFFICE.

JAMES MACPHAIL, OF BLUE ISLAND, ILLINOIS, ASSIGNOR TO THE PLANO MANUFACTURING COMPANY, OF CHICAGO, ILLINOIS.

HAY-RAKE.

SPECIFICATION forming part of Letters Patent No. 638,873, dated December 12, 1899.

Application filed November 16, 1896. Renewed November 8, 1899. Serial No. 736,286. (No model.)

To all whom it may concern:

Be it known that I, JAMES MACPHAIL, a citizen of the United States, residing at Blue Island, in the county of Cook and State of Illinois, have invented a certain new and useful Improvement in Hay-Rakes, which is fully set forth in the following specification, reference being had to the accompanying drawings, in which—

10 Figure 1 is a plan view showing a hay-rake constructed according to my invention. Fig. 2 is a vertical longitudinal section on the line 2 2 of Fig. 1. Fig. 3 is an enlarged plan view of the mounting of the stripper-shaft, rake-teeth, &c. Fig. 4 is a vertical section on the line 4 4 of Fig. 1, showing the same parts. Fig. 5 is a detail rear elevation of the axle and its supports. Fig. 6 is a vertical section on the line 6 6 of Fig. 5. Fig. 7 is a detail 15 view of one of the stripper-shaft bearings. Fig. 8 is a section on the line 8 8 of Fig. 1, showing the attachment of the strippers to the stripper-shaft. Fig. 9 is a vertical section on the line 9 9 of Fig. 8.

20 25 My invention relates to hay-rakes, and has for its object to provide improved mechanism for cleaning or stripping the rake-teeth.

Referring to the drawings by letter, A represents the thills or shafts, and B B, &c., the 30 main frame of the hay-rake. The sides of the said frame B are prolonged backward, as at b, to form bearings for the pivotal connection of the main frame with the wheel-frame. The seat B' is mounted upon the frame B.

35 40 The principal element of the wheel-frame is the angle-iron C, comprising an upper forwardly-extending horizontal flange C' and a vertical flange C². To the flange C², at each end thereof, is secured one of the axle-brackets D, which comprises an axle proper, D', upon which is mounted the wheel E; a cup D², surrounding the said axle D', against which the wheel-hub abuts; two collars D³, and a bracket-plate D⁴, all of the said parts 45 being formed in a single casting and adapted to be secured to the flange C² of the angle-iron by the bolts d. To the said flange C² of the angle-iron are further attached two brackets F, projecting forward and each provided 50 with a short downwardly-extending arm F' and an upwardly-extending arm F². The arm

F' is provided with a pin f, which is pivotally mounted in the projection b of the main frame B. The main frame and the wheel-frame are thus pivotally connected. The upper arm F² 55 of the bracket is provided with the spring-controlled plunger or buffer f', adapted to contact with the side of the main frame B when the rake is tilted. Upon the angle-iron C is rigidly mounted a lever G, to which is pivoted, as at g, a spring-controlled dog G', adapted to engage with the teeth of a segmental rack G², also pivoted to the lever G, as at g'. A connecting-rod H is pivotally secured at one end to the rack-segment G², as at h, and 60 at its other end, as at h', to a hand-lever I. The lever I is pivotally mounted at its lower end, as at i, upon the main frame B. Between its handle I' and its point of connection with the connecting-rod H the said lever is 65 provided with a lug or stop i'. 70

It will be seen that when the hand-lever is thrown upward and forward the main frame is depressed with reference to the wheel-frame and the said wheel-frame is tilted so as to 75 elevate the rake. When the lever I is again thrown back, the rake drops to its normal position and the stop i' bears against the connecting-rod H. An adjustment of the dog G' upon the rack G² will control the position 80 of the rake-teeth in their normal lower position. The said rake-teeth J are mounted in pairs upon the upper flange C' of the angle-iron C by means of the double clamping-plates K, adapted to receive and hold against 85 the said flange the bent ends of the said teeth. Two or more of the said clamping-plates are provided with the bracket extension L. To each bracket is secured a bar M, provided with vertically-elongated apertures M', adapted 90 to receive and guide the rake-teeth.

Referring now more particularly to the strippers, I show five such strippers N, which are preferably metal rods, which may be either of spring metal or not. Each of the said stripper ends near its butt is driven into the head O of a clamping-pin O', which said head is provided with an aperture o for that purpose. The said head O is beveled, as at o', to fit in the groove o² of a clamping-washer O². The 95 said washer, which is concave on its lower surface, is adapted to fit on the outside of the

stripper rock-shaft P, which is preferably hollow, and is held upon the said rock-shaft by the clamping-pin O', which passes through both the washer and the shaft and is bolted 5 on the opposite side of the latter, preferably with a second washer O³. The strippers N are thus rigidly secured to the rock-shaft P.

To the rearward extension b of the main frame are secured bracket-castings Q, each of 10 which is provided with a bearing Q', within which the rock-shaft P is mounted and adapted to rock. The said bracket-casting Q is further provided with a short arm Q², upon 15 the lower surface of which is mounted a lug q. Upon the rock-shaft P, adjacent to each bearing, is bolted a second bracket-casting R, provided with a short arm R', upon the upper surface of which is mounted a lug r, which is thus disposed vertically beneath the 20 lug q. Between these two lugs and surrounding the same is mounted a coiled expansion-spring R², which thus operates to rotate the rock-shaft and to hold the strippers down in a normal position. A limit to this movement 25 is fixed by providing the bracket-casting R with a lug or stop r', which is adapted to bear against the rear bar of the mainframe B when the strippers are in a normal position. By this construction it will be obvious that the 30 strippers, even when of rigid material, are adapted to yield upwardly under an excess of pressure, and thereby prevent fracture of the same. Furthermore, by making the said strippers of spring metal a double elasticity 35 may be obtained—namely, that of the strippers themselves and that of their mounting.

It will be obvious that many changes in the details shown may be made without departing from the principle of my invention. I do 40 not therefore limit myself to the specific devices referred to; but

What I claim, and desire to secure by Letters Patent, is—

1. In a hay-rake, the combination with the 45 frame, of the wheels, the axles therefor, the tooth-supporting bar pivotally mounted in relation to said wheels, the rock-shaft P carrying the stripper-arms N rigidly secured thereto, spring connections between the rock-shaft 50 and the frame for yieldingly holding said rock-shaft and its arms N in a downward position, and stops for preventing the downward movement of the arms N and the shaft P below their normal position, substantially as described.

2. The combination with the frame, of the 55 wheels, the axles therefor, the tooth-supporting bar pivotally mounted in relation to said

wheels, the rock-shaft P carrying the stripper-arms rigidly secured thereto, spring connections between the rock-shaft and the frame for yieldingly holding said rock-shaft and its arms N in a downward position, comprising the brackets R and Q having thereon the lugs r and q and carried by the rock-shaft and the 60 frame respectively, and the helically-coiled expanding spring R² interposed between said lugs, and stops for preventing the downward movement of the arms N and the shaft P below their normal position.

3. In a hay-rake, the rock-shaft P mounted in the main frame in front of the axle; the strippers mounted upon the said rock-shaft, and projecting rearwardly; the bracket R mounted upon the said rock-shaft and provided with an extension R' and with a stop r' 70 adapted to contact with the frame to limit the downward movement of the strippers; the bracket Q mounted upon the frame, and provided with an extension Q²; and the expanding spring R², mounted between the extensions R' and Q² and adapted to hold the strippers yieldingly downward, substantially as described.

4. In a hay-rake, the combination with the 85 frame, of the wheels, the axles therefor, the tooth-supporting bar pivotally mounted in relation to said wheels, the rock-shaft P carrying the spring-metal stripper-arms N rigidly secured thereto, spring connections between 90 the rock-shaft and the frame for yieldingly holding said rock-shaft and its elastic arms N in a downward position, and stops for preventing the downward movement of the arms N and the shaft P below their normal position, substantially as described.

5. In a ray-rake, the rock-shaft P mounted in the framework of the machine forward of the axle; the rearwardly-projecting strippers N, of spring metal, mounted upon the said rock-shaft; the bracket R mounted upon the said shaft, provided with the rearward extension R' and with a forwardly-extending stop r' adapted to contact with the framework and limit the downward movement of the strippers; the bracket Q mounted upon the framework provided with the extension Q²; and the expanding spring R², mounted between the extensions R' and Q², and adapted to hold the strippers yieldingly downward, substantially as described.

JAMES MACPHAIL.
